UNITED STATES PATENT OFFICE.

NATHAN M. MARKOWITZ, OF BROOKLYN, NEW YORK, ASSIGNOR TO GLOBE MATCH CORPORATION, A CORPORATION OF DELAWARE.

MATCH-PACKETING MACHINE.

Application filed May 12, 1923. Serial No. 638,559.

To all whom it may concern:

Be it known that I, NATHAN M. MARKOWITZ, citizen of the United States, residing at 364 41st Street, Brooklyn, in the county 5 of Kings and State of New York, have invented certain new and useful Improvements in Match-Packeting Machines, of which the following is a specification.

This invention relates to match packeting machines, and has special reference to a machine for assembling match strips and their covers to form the match packets which are known as vest pocket packets, and which consist of a strip, usually of paper, split to 10 form individual matches and having the individual splints thus formed tipped with a match composition, and a strip of cardboard, pasteboard or the like, wrapped around the strip of matches with the latter 15 stapled or otherwise secured to the cardboard.

One important object of the present invention is to provide an improved and novel construction of machine wherein strips of 20 matches and a strip of cardboard or the like are fed beneath an assembling head which operates to cut off the strips of matches to the proper width, place them in proper position on a wrapped blank, and then fold 25 the blank about them.

A second important object of the invention is the provision of improved means for insuring the proper feeding and cutting of 30 the match strips.

A third important object of the invention 35 is the provision of improved means for folding the wrapper blank about the match strip after it has been cut.

A fourth important object of the invention 40 is to provide an improved mechanism for simultaneously feeding a wrapper blank and the proper length of match strip into position for assembling.

With the above and other objects in view 45 as will be hereinafter apparent, the invention consists in general of certain novel details of construction and combinations of parts which will be hereinafter fully described, illustrated in the accompanying 50 drawings and specifically claimed.

In the accompanying drawings like characters of reference indicate like parts in the several views, and:

Fig. 1 is a plan view of the improved match packet assembling machine, showing 55 the same in position on its working table.

Fig. 2 is a side elevation of the machine as it appears from the lower side of Fig. 1.

Fig. 3 is an enlarged detail section taken on the line 3—3 of Fig. 1, and disclosing 60 the assembling mechanism in elevation.

Fig. 4 is a section on the same scale as Fig. 3, but taken on the line 4—4 of Fig. 1.

Fig. 5 is a still further enlarged detail taken on the line 5—5 of Fig. 1, and disclosing 65 a blank and a strip of matches ready for the assembling operation beneath the presser head.

Fig. 6 is a view similar to Fig. 5, but showing the various parts in the position 70 which they assume after the presser head or plunger has descended, and the packet top folding mechanism has operated to fold down the packet top.

Fig. 7 is a view similar to Figures 5 and 75 6, but disclosing a further step in the operation wherein the ejector plunger is operating to eject the match packet from the position shown in Figures 5 and 6 through the bottom end folding mechanism.

Fig. 8 is a view on the same scale as Figures 5, 6 and 7, the illustration being a section taken through the magazine and showing the ends of the match strip in position 80 beneath the presser head or plunger ready to be cut off, a wrapper blank being in position to be operated on beneath the match strip end.

Fig. 9 is a view similar to Fig. 8, but showing the end of the match strip cut off 85 and centered on the wrapper blank.

Fig. 10 is a view similar to Fig. 8, but showing the presser head or plunger in its lowermost position.

Fig. 11 is a view similar to Fig. 8, but 90 showing the presser head retracted to its uppermost position in order to permit operation of the top end folding mechanism of the blank.

Fig. 12 is a detail of the underside of the 100 ejector plunger shown in Fig. 7.

Fig. 13 is a detail view of a certain cam, also shown in Fig. 7.

Fig. 14 is a top plan view of the top end 105 folding finger shown in Fig. 7.

Fig. 15 is a view of the part shown in Fig.

14, taken from the opposite side of the showing in Fig. 7.

Fig. 16 is a diagrammatic view illustrating the relationship of a wrapper blank and the end of a match strip before the latter are assembled beneath the plunger.

Fig. 17 is a plan view showing the match strip end severed and assembled on the wrapper blank.

10 Fig. 18 is a view of the match strip and wrapper blank assembled beneath the plunger ready for the first folding operation.

15 Fig. 19 is a view similar to Fig. 18, but showing the first folding operation completed.

Fig. 20 is a view showing the folding operations substantially completed and the packet beginning to be ejected.

20 Fig. 21 is a side view of the complete packet.

In the present embodiment of the invention, there is provided a table 30, which has on one side a slot 31 beneath which may be placed a receptacle for receiving the completed match packets. Extending transversely of this table and journaled in suitable bearings, not deemed necessary to be shown, is a shaft 32, whereon is fixed a belt wheel 33, which may be belted to any suitable source of power for driving the entire machine. It is to be understood that this belt wheel may be replaced by a motor, either directly connected to the shaft 32, or geared thereto, as may be desired. On the top of the table and extending across the direction of the shaft 32, there is provided a conveyor housing 34, through which passes an endless chain 35 having at definitely spaced intervals certain projections or fingers 36. This endless chain runs over a sprocket wheel 37 extending upwardly through a slot 38 in the bottom of the table, so that the upper run of the chain rests on the top of the table beneath the housing and the fingers 36 on this upper run project upwardly. The sprocket wheel 37 is mounted on a shaft 39 carried in suitable bearings, not shown, and on one side of this sprocket wheel is a ratchet member 40. On the shaft 39 is mounted a rocker 41 carrying a pawl 42 which engages with the ratchet 40 to intermittently operate the same. Fixed on the shaft 32 is an eccentric 43 which is surrounded by a suitable eccentric strap 44, and from one side of this strap extends an eccentric rod 45 which is pivotally connected to the rocker 41. By means of this construction rotation of the shaft 32 actuates the eccentric 43, and thus causes oscillation of the rocker 41. Under these conditions, it will be obvious that the chain 35 is driven by an intermittent motion, and the arrangement of the parts is such that the direction of motion of the chain causes travel of its upper run

toward an assembling station, indicated in general at A. At the assembling station A, there is provided a depression 46 constituting a primary folding die. The conveyor housing terminates on one side of this depression, while on the opposite side there is provided a magazine 47 wherein may be placed a stack of wrapper blanks 48, each consisting of a rectangular strip of pasteboard, cardboard, or the like, and each of the proper width to fit the width of the depression or die 46. On one side of the magazine, there is provided a vertically aligned pair of guide bearings 49 wherein is slidably mounted a plunger stem 50, having a head 51 fixed to its lower end, and provided on each side with the plates 52 and 53. The plate 52 constitutes a cutter knife, and has its lower end bevelled inwardly with respect to the head 51, as shown at 54. 85 This plate cooperates with a stationary cutter knife 55 forming one side of the recess 46.

The plate 53 is bevelled opposite to 54, and it will be observed by an inspection of Fig. 4, as well as by an inspection of Fig. 9, that the oppositely bevelled edges of these plates constitute centering means for cut off portions of a match strip, as will be herein-after described. Adjacent the conveyor housing, there is provided on the table 30 a standard 56, and this standard carries a stub shaft 57 which passes through a boss 58 located between the ends of an oscillating lever 59. One end of this lever 59 is provided with a fork 60 between the arms of which is received a roller 61 carried on a stub pin 62 fixed to one side of the plunger stem 50. The other end of this lever 59 is pivotally connected to an adjustable link 105 63, carrying on its lower end a fork 64 which straddles the shaft 32. At the junction of the stem of this link with the fork, there is provided a cam roller 65 which works in a cam groove 66 formed in a cam 67 fixed 110 on the shaft 32. Thus, under these conditions, rotation of the shaft 32 will cause reciprocation of the link 63 and this in turn will oscillate the lever 59 and reciprocate the plunger or presser.

Fixed upon the table 30 on the side of the assembling table opposite the conveyor is a pair of guides 68 beneath which moves a reciprocating blank ejector bar 69 carrying at the end adjacent the assembling station, an ejector plate 70. This plate 70 reciprocates beneath the magazine 47, suitable openings being provided at each side of the magazine for this purpose, and the plate 70 is of substantially the same thickness as 125 the material used for the blanks 48. Depending from the bar 69 is a hanger 71 to which is connected pivotally one end of a link 72, the other end of which is connected to a pivot pin 73 carried by the rocker 41. 130

It will be observed that the pawl 42 is on one side of the shaft 39, while the pivot pin 73 is virtually on the opposite side thereof so that as the pawl operates, upon oscillation 5 in feeding direction of the rocker 41, to feed the chain forward, the ejector bar 69 also operates to feed a blank toward the station A. It should here be noted that there is provided under the conveyor housing, 0 a pair of supporting rails 74 between which the chain moves and which serve to support the longer match strips 75, of which preferably two are used, one superposed on the other, and these match strips are provided 5 at intervals corresponding to the width of the short sections used in each packet with openings 76 for engagement by the teeth 36 on the chain.

It will now be obvious that there will be an 0 intermittent feeding of the match strips to the station A at the same time that there is a feeding of one of the blanks 48 to this station and, by reference to Fig. 4, it will be seen that the parts are so proportioned 5 and arranged that the wrapper blank 48 is fed beneath the projecting end of the longer match strips. It is, of course, essential that the various parts just described, be so proportioned that the proper length 0 of match strip will be fed to the assembling station, and that the proper stroke of the blank ejector bar 69 be obtained simultaneously with this feeding.

Moreover, it will be obvious that the motion of the plunger and cutter is to be so timed with relation to these other movements that during the pause in the operation of the chain, the plunger will descend from the position shown in Fig. 8 through the position shown in Fig. 9 to the position shown in Fig. 10, and that this operation will first sever what may be termed the packet strip from the main strip, will then center this severed portion on the blank, and will next force the blank and the severed portion down to the bottom of the die 46. By reference to Fig. 3, it will be observed that a cover plate 77 is provided on top of one of the rails 74 for the slot in which the chain operates, and that one or more spring fingers 78 may be provided beneath the housing 34 for holding the longer strips downward on the supporting rails 74.

Considering now the folding and ejecting mechanism. It will be observed from Fig. 3, that there is provided on the shaft 32 a cam 79 having in its edge a cam groove 80 wherein is received a pin or roller 81 carried by one end of an oscillating lever 82 which is pivoted intermediate its ends to the underside of the bed or table 30. This oscillating lever has its remaining end connected to a packet ejector bar 83, which slides beneath guide members 84 fixed on the table 30 at right angles to the conveyor,

and on the side of the assembling station opposite the delivery slot 31 of said table.

This packet ejector bar is adapted to move into and out of the die 46 beneath a guide plate 85, which forms one end of said die, 70 and is fixed with relation to the table. The other end of the die is formed by a movable plate 86 which has its underside bevelled as at 87, and is supported by a stem 88 moving in a guide bearing 89, the plate 86 being normally pressed downward by means of a spring 90 surrounding said stem 88 between the upper surface of the plate and the guide 89.

It will be observed that both the plate 85 and the plate 86 are provided with shoulered portions 91, which serve to properly position the blanks 48 as they are fed into folding position. Moreover, it will now be noted, by reference to Fig. 19, that at the same time the packet forming plunger descends in the operation of cutting and centering the match packet strips on the blanks, the central portion of these blanks will be forced down to the bottom of the die 46, 80 while the end portions will be caused to turn vertically upward by the action of the respective plates 85 and 86, it being noted that the end near the plate 86 is the bottom end of the packet and is shorter than 90 the top end near the plate 85. The member 83 is channelled at its undersides as at 92, and pivoted within this channelled portion is a spring pressed pawl or latch member 93 having a square forward end 94 behind which in spaced relation thereto is a bevelled shoulder 95. Beneath the forward end of the member 83, there is provided, in the table, a slot 96, and at 97 is a cam lever which is pivoted at 98 below the table, and which has a cam projection 99 extending up through the slot 96 so that, as the pawl 93 is carried forward, the end 94 engages this cam projection and forces the lever 97 downwardly at its free forward end 100 while, after the member 83 has passed to such position that the cam projection 99 is cleared by the pawl 93 and then returns, the bevelled surface 95 permitting free backward passage of the pawl without disturbing the lever 97.

Depending below the table is a bracket 100, whereto is pivotally connected a rock arm 101 having a laterally projecting end 102, which engages beneath a corresponding laterally projecting end 103 formed on the lever 97. The remaining end of this rock arm 101 swings through the slot 96 and carries a curved folding finger 104 having at its free end a laterally projecting portion 105. The arrangement of these parts is such that lever 101 is operated each time the lever 97 has its free end depressed, and this operation forces the folding finger 104 forwardly into engagement with the up- 110 120 125 130

standing longer or top end of the blank in its position, as shown in Fig. 19, and bends this end downwardly, as shown in Fig. 6.

It will be noted that owing to the fact 5 that the pawl 93 has its operating end of some length, the finger 104 will be held temporarily in this position during further forward movement of the bar 83.

Now referring particularly to Figures 6 10 and 7, it will there be seen that after the movement just described, the bar 83 continues to move forward, and pushes the partly folded packet beneath the plate 86, which effects folding of the shorter end or bottom 15 end of the wrapper blank unto the longer upper end in the manner disclosed in Fig. 7, and also in Fig. 20. The bar 83 moves sufficiently far forward to force the entire packet into the position shown in Fig. 5, 20 and in its movement to this position, the previously folded packet is carried forward.

It will be further observed from Fig. 5, 25 that under the conditions there shown, the smaller or lower end of the packet projects beyond the support so that a staple 106 may be inserted therein by suitable machinery, and clinching. The machinery for inserting and clinching this staple is not here shown, as it is not desired to disclose the 30 same in connection with the present invention.

Just as in the manner in which the timing 35 of the parts connected with the feeding and assembling of the matches and packet blanks was governed by the proportions of the parts, so are the movements of the folding mechanism timed in relation to the other movements of the device.

The different specific steps in the operation 40 of the machine have been described, but it is though best to briefly state the entire operation of all the elements together, this being as follows:

A pair of match strips having been placed 45 on the conveyor, and a suitable number of blanks placed in the magzine, operations are started. The match strips are fed forward step by step, with pauses between the feeding, and as each packet section of strip is fed forward to the assembling station A, a blank is also fed to this station. The blank and end of the match strip being in position, the plunger descends, cuts off the required length of match strip and centers 50 the same, forces the strip and blank down into the die whereby the ends of the blank are turned up, and retracts. Then the folding mechanism operates first to fold down the longer upper end and next to move the partly folded packet beneath the plate 86 whereby to fold the shorter lower end and eject the folded packet from the assembling 55 station, so that the later is left clear for the assembling and folding of a fresh 60 packet.

There has thus been provided a simple and efficient device of the kind described and for the purpose specified.

It is obvious that minor changes may be made in the form and construction of the 7 invention without departing from the material spirit thereof. It is not, therefore, desired to confine the invention to the exact form herein shown and described, but it is desired to include all such as properly 7 come within the scope claimed. For instance, the chain may be replaced by a suitable pawl and ratchet mechanism, it being merely necessary that a step by step feed 8 be provided.

Having thus described the invention, what is claimed as new, is:

1. In a machine of the class described, an assembling station, means to feed a strip of matches to said station intermittently, other means to feed packet wrapping material to said station, and a combined cutting off and centering mechanism at said station arranged to operate on the match strip to cut off a portion of the same and center it on the wrapping material.

2. In a machine of the class described, an assembling station, means to feed a strip of matches into said station intermittently, means to feed a wrapper blank to said station beneath the end of the match strip, and a combined cutting off and centering device at said station arranged to operate on the portion of the strip of matches at the station to sever the same from the remainder of the strip and center it on the blank.

3. In a machine of the class described, an assembling station, means to feed successive match strip sections to said station, other means to feed successive wrapper blanks to said station beneath the respective match strip sections, and a combined match strip section centering and wrapper end folding element at said station.

4. In a machine of the class described, an assembling station, means to feed successive match strip sections to said station, other means to feed successive wrapper blanks to said station beneath the respective match strip sections, and a plunger reciprocably supported at said station and having a head provided with guides for engaging the match strip sections as they are delivered to the assembling station and centering them on the respective blanks.

5. In a machine of the class described, an assembling station, means to feed a long match strip to said station intermittently 11 whereby to cause projection of successive sections into the station, and a reciprocable plunger at said station carrying a pair of bevelled plates projecting from its lower end, one of said plates having its bevelled portion sharpened to constitute a strip cut-

ting element whereby to sever the projecting section from the remainder of the strip, said plates having the bevelled portions confronting each other on opposite sides of the assembling station whereby to center the severed portions relative to said station.

6. In a machine of the class described, an assembling station, means to feed a long match strip to said station intermittently whereby to cause projection of successive sections into the station, a reciprocable plunger at said station carrying a pair of bevelled plates projecting from its lower end, one of said plates having its bevelled portion sharpened to constitute a strip cutting element whereby to sever the projection section from the remainder of the strip, said plates having the bevelled portions confronting each other on opposite sides of the assembling station whereby to center the severed portions relative to said station, and means to feed a series of wrapper blanks successively into said station.

7. In a machine of the class described, an assembling station, means to feed a long match strip to said station intermittently whereby to cause projection of successive sections into the station, a reciprocable plunger at said station carrying a pair of bevelled plates projecting from its lower end, one of said plates having its bevelled portion sharpened to constitute a strip cutting element whereby to sever the projecting section from the remainder of the strip, said plates having the bevelled portions confronting each other on opposite sides of the assembling station whereby to center the severed portion relative to said station, said assembling station including a die into and out of which said plunger moves, said die having ends cooperating with the plunger to form wrapper blank end folding means, and means to feed a series of wrapper blanks successively into said station beneath the projecting portions of the match strip and over said die.

8. In a machine of the class described, an assembling station, means to feed a long match strip to said station intermittently whereby to cause projection of successive sections into the station, a reciprocable plunger at said station carrying a pair of bevelled plates projecting from its lower end, one of said plates having its bevelled portion sharpened to constitute a strip cutting element whereby to sever the projecting section from the remainder of the strip, said plates having the bevelled portions confronting each other on opposite sides of the assembling station whereby to center the severed portion relative to said station, said assembling station including a die into and out of which said plunger moves, said die having ends cooperating with the plunger to form wrapper blank end folding means,

means to feed a series of wrapper blanks successively into said station beneath the projecting portions of the match strip and over said die, and mechanism at the assembling station for completing the folding of the 70 wrappers and ejecting the folded packets.

9. In a machine of the class described, an assembling station, means to project successive sections of a match strip into said station intermittently; other means to feed 75 successive wrapper blanks into said station, and a single intermittently movable element operating on the projecting strip sections and blanks and provided with means for severing the projecting section from the body 80 of the strip and centering it on the blank, said element being arranged to constitute a blank end folding means.

10. In a machine of the class described, an assembling station, intermittently operating 85 means to feed a match strip into said station whereby successive portions of the strip are intermittently projected into the station, other means to feed successive wrapper blanks into said station beneath the projecting portion of the match strip, said means being operable in unison with the strip feeding means, and a single intermittently movable element operating on the projecting strip sections 90 and blanks and provided with means for severing the projecting section from the body of the match strip and centering the same on its blank, said element being arranged to constitute a blank end folding 95 means and operating in alternation with the first mentioned means.

11. In a machine of the class described, an assembling station, means to project successive sections of a match strip into said station intermittently; other means to feed 105 successive wrapper blanks into said station, a single intermittently movable element operating on the projecting strip sections and blanks and provided with means for severing the projecting section from the body of the strip and centering it on the blank, said element being arranged to constitute a blank end folding means, and other folding and ejecting means arranged to complete the folding of the packet at the assembling 110 station and to eject it from said station.

12. In a machine of the class described, an assembling station, intermittently operating means to feed a match strip into said station whereby successive portions of the strip are intermittently projected into the station, other means to feed successive wrapper blanks into said station beneath the projecting portion of the match strip, said 120 means being operable in unison with the strip feeding means, a single intermittently movable element operating on the projecting strip sections and blanks and provided with means for severing the projecting section from the body of the match strip and cen- 125

tering the same on its blank, said element being arranged to constitute a blank end folding means and operating in alternation with the first mentioned means, and other 5 folding and ejecting means arranged to complete the folding of the packet at the assembling station and to eject it from said station.

13. In a machine of the class described, a revolute shaft, a match strip conveyor including an endless chain having match strip engaging teeth thereon, a sprocket wheel, supporting and driving said chain, a ratchet wheel carried by the sprocket wheel, a rocker mounted to swing concentrically 10 of the sprocket wheel, a pawl on said rocker engaging said ratchet, crank means on the shaft connected to the rocker to oscillate the same, a wrapper blank magazine, opposite the end of the conveyor, a reciprocable feeder beneath the lower end of the magazine, and a link connecting said feeder and rocker and positioned on the rocker to cause feeding movement of the feeder simultaneously with feeding movement of the chain. 20

14. In a machine of the class described, a revolute shaft, a match strip conveyor including an endless chain having match strip engaging teeth thereon, a sprocket wheel supporting and driving said chain, a ratchet wheel carried by the sprocket wheel, a rocker mounted to swing concentrically of the sprocket wheel, a pawl on said rocker engaging said ratchet, crank means on the shaft connected to the rocker to oscillate the same, a wrapper blank magazine, opposite the end of the conveyor, a reciprocable feeder beneath the lower end of the magazine, a link connecting said feeder and rocker and positioned on the rocker to cause feeding movement of the feeder simultaneously with feeding movement of the chain, an assembling station into which the chain moves successive portions of the match strip and the feeder moves successive blanks located between the conveyor and magazine, and means at the magazine for severing the match strip and folding the blank about the severed position. 30

15. In a machine of the class described, a magazine for wrapper blanks, a die at one side of said magazine, single delivery means for said blanks to move the same from the magazine to position over the die, a reciprocating plunger over the die, and movable into and out of said die, said die having substantially perpendicular end walls, means to deliver match strip sections onto the successive blanks, a match strip centering means on said die, said plunger being of slightly less length than the die to permit the blank ends to fold up upon depression of the plunger, a folding finger mounted at one end of the die for oscillatory movement, means to move said finger forwardly against an up-

standing end of the blank and depress said end, said means being arranged to hold the finger temporarily in end depressing position, and means to move the folded blank forwardly from under said finger. 70

16. In a machine of the class described, an assembling station, means to assemble match strip sections and wrapper blanks at said station with each end of the blanks turned upward, one end of said assembling station being provided with an abutment and folder plate spaced to provide an ejection opening, an ejector bar reciprocable through the station at predetermined intervals, and an end folding mechanism actuated by the movement of the ejector bar to fold down one of the upwardly turned blank ends. 75

17. In a machine of the class described, an assembling station, means to assemble match strip sections and wrapper blanks at said station with each end of the blanks turned upward, one end of said assembling station being provided with an abutment and folder plate spaced to provide an ejection opening, an ejector bar reciprocable through the station at predetermined intervals, and an end folding mechanism actuated by the movement of the ejector bar to fold down one of the upwardly turned blank ends, said end folding mechanism being turned to complete the folding of the respective end prior to engagement of the packet by the ejector bar. 80

18. In a machine of the class described, an assembling station, means to assemble match strip sections and wrapper blanks at said station with each end of the blanks turned upward, one end of said assembling station being provided with an abutment and folder plate spaced to provide an ejection opening, an ejector bar reciprocable through the station at predetermined intervals, and an end folding mechanism actuated by the movement of the ejector bar to fold down one of the upwardly turned blank ends, said end folding mechanism being turned to complete the folding of the respective end prior to engagement of the packet by the ejector bar and arranged to retain said blank end in folded position during primary movement of the packet. 100

19. In a machine of the class described, an assembling station, means to assemble match strip sections and wrapper blanks at said station with each end of the blanks turned upward, one end of said assembling station being provided with an abutment and folder plate spaced to provide an ejection opening, an ejector bar reciprocable through the station at predetermined intervals, an oscillating cam lever, a pawl carried by the ejector bar and arranged to engage the cam portion of the lever and move the lever in one direction upon movement of the ejector 110 120 125 130

bar in packet ejecting direction, a second oscillating lever engageable by the first lever and provided with a folding finger, said second lever being positioned to cause engagement of the folding finger with the packet end and bend it to folded position.

20. In a machine of the class described, an assembling station, means to assemble match strip sections and wrapper blanks at said station with each end of the blanks turned upward, one end of said assembling station being provided with an abutment and folder plate spaced to provide an ejection opening, an ejector bar reciprocable through the station at predetermined intervals, an oscillating cam lever, a pawl carried by the ejector bar and arranged to engage the cam portion of the lever and move the lever in one direction upon movement of the ejector bar in packet ejecting direction, a second oscillating lever engageable by the first lever and provided with a folding finger, said second lever being positioned to cause engagement of the folding finger with the packet end and bend it to folded position, said pawl being positioned on the bar to cause folding movements of said levers prior to engagement of the packet by the bar.

21. In a machine of the class described, an assembling station, means to assemble match strip sections and wrapper blanks at said station with each end of the blanks turned upward, one end of said assembling station being provided with an abutment and folder plate spaced to provide an ejection opening, an ejector bar reciprocable through the station at predetermined intervals, an oscillating cam lever, a pawl carried by the ejector bar and arranged to engage the cam portion of the lever and move the lever in one direction upon movement of the ejector bar in packet ejecting direction, a second oscillating lever engageable by the first lever and provided with a folding finger, said second lever being positioned to cause engagement of the folding finger with the packet end and bend it to folded position, said pawl being positioned on the bar to cause folding movements of said levers prior to engagement of the packet by the bar, said pawl and cam lever being arranged to cause dwell of the cam lever in wrapper and folding position during the first portion of the engagement of the ejector bar with the packet.

22. In a machine of the class described, an assembling station, means to assemble match sections and wrapper blanks at said station with each end of the blanks turned upward, one end of said assembling station being provided with an abutment and folder plate spaced to provide an ejection opening, vertically yieldable support for said plate whereby to permit variation in the size of the ejection opening, an ejector bar reciprocable through the station at predetermined intervals, an oscillating cam lever, a pawl carried by the ejector bar and arranged to engage the cam portion of the lever and move the lever in one direction upon movement of the ejector bar in packet ejecting direction, a second oscillating lever engageable by the first lever and provided with a folding finger, said second lever being positioned to cause engagement of the folding finger with the packet end and bend it to folded position.

ciprocable through the station at predetermined intervals, and an end folding mechanism actuated by the movement of the ejector bar to fold down one of the upwardly turned blank ends.

23. In a machine of the class described, an assembling station, means to assemble match strip sections and wrapper blanks at said station with each end of the blanks turned upward, one end of said assembling station being provided with an abutment and folder plate spaced to provide an ejection opening, vertically yieldable support for said plate whereby to permit variation in size of the ejection opening, an ejector bar reciprocable through the station at predetermined intervals, and an end folding mechanism actuated by the movement of the ejector bar to fold down one of the upwardly turned blank ends, said end folding mechanism being turned to complete the folding of the respective end prior to engagement of the packet by the ejector bar.

24. In a machine of the class described, an assembling station, means to assemble match strip sections and wrapper blanks at said station with each end of the blanks turned upward, one end of said assembling station being provided with an abutment and folder plate spaced to provide an ejection opening, vertically yieldable support for said plate whereby to permit variation in the size of the ejection opening, an ejector bar reciprocable through the station at predetermined intervals, and an end folding mechanism actuated by the movement of the ejector bar to fold down one of the upwardly turned blank ends, said end folding mechanism being turned to complete the folding of the respective end prior to engagement of the packet by the ejector bar and arranged to retain said blank end in folded position during primary movement of the packet.

25. In a machine of the class described, an assembling station, means to assemble match strip sections and wrapper blanks at said station with each end of the blanks turned upward, one end of said assembling stations being provided with an abutment and folder plate spaced to provide an ejection opening, vertically yieldable support for said plate whereby to permit variation in the size of the ejection opening, an ejector bar reciprocable through the station at predetermined intervals, an oscillating cam lever, a pawl carried by the ejector bar and arranged to engage the cam portion of the lever and move the lever in one direction upon movement of the ejector bar in packet

ejecting direction, a second oscillating lever engageable by the first lever and provided with a folding finger, said second lever being positioned to cause engagement of the folding finger with the packet end and bend it to folded position.

26. In a machine of the class described, an assembling station, means to assemble match strip sections and wrapper blanks at said station with each end of the blanks turned upward, one end of said assembling station being provided with an abutment and folder plate spaced to provide an ejection opening, vertically yieldable support for said plate whereby to permit variation in the size of the ejection opening, an ejector bar reciprocable through the station at predetermined intervals, an oscillating cam lever, a pawl carried by the ejector bar and arranged to engage the cam portion of the lever and move the lever in one direction upon movement of the ejector bar in packet ejecting direction, a second oscillating lever engageable by the first lever and provided with a folding finger, said second lever being positioned to cause engagement of the folding finger with the packet end and bend it to folded position, said pawl being positioned on the bar to cause folding movements of said levers prior to engagement of the packet by the bar.

27. In a machine of the class described, an assembling station, means to assemble match strip sections and wrapper blanks at said station with each end of the blanks

turned upward, one end of said assembling station being provided with an abutment and folder plate spaced to provide an ejection opening, vertically yieldable support for said plate whereby to permit variation in the size of the ejection opening, an ejector bar reciprocable through the station at predetermined intervals, an oscillating cam lever, a pawl carried by the ejector bar and arranged to engage the cam portion of the lever and move the lever in one direction 40 upon movement of the ejector bar in packet ejecting direction, a second oscillating lever engageable by the first lever and provided with a folding finger, said second lever being positioned to cause engagement of the 45 folding finger with the packet end and bend it to folded position, said pawl being positioned on the bar to cause folding movements of said lever prior to engagement of the packet by the bar, said pawl and cam 50 lever being arranged to cause dwell of the cam lever in wrapper and folding position during the first portion of the engagement of the ejector bar with the packet.

In testimony whereof I have affixed my 55 signature.

NATHAN M. MARKOWITZ.
